UNITED STATES PATENT OFFICE.

DANIEL W. COE, OF MONTREAL, QUEBEC, CANADA, ASSIGNOR TO MEAD-MORRISON MANUFACTURING COMPANY, OF EAST BOSTON, MASSACHUSETTS, A CORPORATION OF MAINE.

ENDLESS-CHAIN CONVEYER.

Application filed April 26, 1922. Serial No. 556,652.

To all whom it may concern:

Be it known that I, DANIEL W. COE, a citizen of the United States, and a resident of Montreal, in the Province of Quebec and 5 Dominion of Canada, have invented an Improvement in Endless-Chain Conveyers, of which the following description, in connection with the accompanying drawings, is a specification, like characters on the drawings 10 representing like parts.

This invention aims to provide a novel and improved endless chain conveyer, having many advantages, among them low cost of manufacture, great strength and durability, and convenience and low cost of replacement of worn parts.

The invention will be best understood by reference to the following description, when taken in connection with the accompanying 20 drawings of one specific embodiment thereof, while its scope will be more particularly pointed out in the appended claims.

In the drawings:

Fig. 1 is an elevation of a portion of a 25 conveyer exemplifying the invention;

Fig. 2 is a sectional view on an enlarged scale of some of the parts, looking in the same direction as Fig. 1;

Fig. 3 is a sectional view on line 3—3 of 30 Fig. 2;

Fig. 4 is a perspective view of a terminal portion of one of the links and a portion of the shaft which is received therein; and

Fig. 5 is a perspective view of the opposite terminal portion of another link, and a bushing which is received therein and presents a bearing for the shaft shown in Fig. 4.

Referring to the drawings, and to the embodiment of the invention which is selected for exemplification, and having reference first to Fig. 1, there is shown a conveyer comprising a chain made up of a series of sets of links, each set comprising two pairs, 45 and each pair being composed of two links 6 and 8. The several sets of links are pivotally connected end to end by pivots 10, which also serve as shafts for wheels 12, which in practice run on usual tracks not herein shown. Each set of links affords a support for a usual gravity bucket 14, having cams 16 secured thereto and presenting bearings for coaxially aligned pivots 18, each

of which receives support in the links of one pair. Each pivot extends through 55 openings provided in both links, and is encircled by a sleeve 20, to which it is secured as by a cotter pin 22, said sleeve constituting a spacer for the links, maintaining a predetermined minimum space between their intermediate portions. Removal of the cotter pins permits the pivots to be withdrawn in outward directions from the bearings in their respective cams, thereby permitting the bucket to be removed from the chain with- 60 out dismounting the latter.

Referring now to Fig. 2, the links 6 and 8 are offset toward each other, thereby affording a relatively wide spacing of one pair of ends, and a relatively narrower spacing 70 of the other pair, the narrowly spaced ends of one pair being received between the widely spaced ends of the next adjacent pair (see Fig. 1). This is conveniently accomplished by employing links composed of 75 steel plates having widely spaced parallel portions 24 and 24', converging portions 26 and 26', and narrowly spaced parallel portions 28 and 28'. In the present example, the links are bent inwardly toward each other, commencing at a point substantially midway between their ends,—that is to say, where the pivots 18 extend therethrough. The form and arrangement of the links is such that each pair, with its connections, 80 possesses a truss-like characteristic, giving the chain great lateral strength and tending to steady the same when in operation. Moreover, the arrangement of the links with relation to the wheel and the shaft is such 85 that the pull on the chain has little tendency to bend the shaft.

Referring now to Fig. 4, the shaft 10 is held against turning movement with relation to the link 6, as by providing said shaft with a flat surface 30, conveniently formed by slabbing the same by means of a milling cutter. The slabbed-off portion of the shaft is received in and held against turning movement by an opening 32 provided in the link 6, the perimeter of which opening is the same shape as the cross-section of the slabbed-off portion of the shaft. The link is held in place on the shaft by a cotter pin 34, and a washer 36 interposed 100 between said pin and the link. The corre-

sponding end of the other link is held in place in a similar manner by a cotter pin 34' and a washer 36'.

The narrowly spaced ends of each pair 5 of links are provided with bushings 38 and 38', affording bearings in which the shaft turns. Turning movement of these bushings in their respective links is prevented by providing each with two flat parallel surfaces 10 faces 40' and 40', conveniently formed by slabbing them off by means of a milling cutter. The links are provided with openings 42 and 42', which receive the bushings, the perimeter of each opening having the same 15 outline as the cross-sectional shape of the slabbed-off portion of its bushing, the latter thereby being held against turning movement in its link, as will be evident from an examination of Fig. 5. Each bushing extends 20 at its opposite ends beyond the link in which it is received, and encircling the projecting ends of the bushing are washers 44 and 44', which present end bearings for the wheel 12, and for the terminal portions 25 of the other pair of links.

Each wheel is provided with a chamber 46, which may be filled with lubricant through a filling plug 48. The lubricant will lubricate the bearings of the wheel on 30 the shaft, and will work along the shaft and lubricate the bearing surfaces of the bushings on the shaft, as well as the washers which receive the end thrust.

The links of the described chain are much 35 stronger and more durable than the malleable iron links usually employed. When wear eventually takes place, it is unnecessary to supply new links, because the wear is taken on the bushings, and it is a simple 40 and inexpensive matter to replace the latter. This is true also of the washers, which, when worn, can be replaced at slight expense.

Having thus described one embodiment of 45 the invention, but without limiting myself thereto, what I claim and desire by Letters Patent to secure is:

1. In a conveyer chain, the combination of 50 a series of links arranged in pairs, one pair of ends of each pair of links being received between the ends of the links of an adjacent pair, a series of wheels, each received between the first-mentioned ends, and a series of shafts on and in contact with 55 which said wheels, respectively, are mounted to turn, said shafts affording the sole pivotal connections between said pairs of links.

2. In a conveyer chain, the combination of 60 a series of links arranged in pairs, one pair of ends of each pair of links being received between the ends of the links of an adjacent pair, a series of wheels, each received between the first-mentioned ends, and a series of shafts on which said wheels, 65 respectively, are mounted to turn, said

shafts affording pivotal connections between said pairs of links and being rotatably mounted in one and non-rotatably mounted in the other.

3. In a conveyer chain, the combination 70 of a series of links arranged in pairs, each pair having one pair of ends spaced apart a lesser distance than the other ends of the same pair of links and being received between the ends of the more widely spaced 75 ends of an adjacent pair, a series of wheels, each received between the more narrowly spaced pair of ends, and a series of shafts on and in contact with which said wheels, respectively, are mounted to turn, said 80 shafts affording the sole pivotal connections between said pairs of links.

4. In a conveyer chain, the combination 85 of a series of links arranged in pairs, the links of each pair having converging sides, thereby affording a wide spacing of one pair of ends and a relatively narrower spacing of the other pair of ends, the narrowly spaced ends of one pair being received between the widely spaced ends of 90 the next adjacent pair, a series of wheels, each received between the narrowly spaced ends of one pair of links, a series of shafts on which said wheels, respectively, are mounted to turn, said shafts affording pivotal 95 connections between said pairs of links, each shaft having non-rotatable engagement with one link of one pair through which it extends, the links of the other pair being provided with bushings having non-rotatable engagement therewith and affording 100 bearings for such shaft.

5. In a chain, the combination of two 105 links, each presenting a non-circular opening, a non-circular bushing non-rotatably received in one of said openings, a pivot 110 presenting a cylindrical part received in said bushing and turning in one link and presenting a non-circular part non-rotatably received in the non-circular opening of the 110 other link.

6. In a chain, the combination of two 115 links, each presenting a non-circular opening, a bushing presenting a non-circular part non-rotatably received in the opening of one of said links, said bushing projecting beyond opposite faces of such link, washers encircling such projecting parts of 120 said bushing on opposite sides, respectively, of such link, and a pivot received and turning in said bushing and presenting a non-circular part non-rotatably received in the non-circular opening of the other link.

7. In a chain, the combination of two 125 links, each presenting a non-circular opening, a bushing presenting a non-circular part non-rotatably received in the opening of one of said links, said bushing projecting beyond opposite faces of such link, washers encircling such projecting parts of 130

said bushing on opposite sides, respectively, of such link, a pivot received and turning in said bushing and presenting a non-circular part non-rotatably received in the 5 non-circular opening of the other link, and a washer encircling said non-circular part of said pivot.

8. In a chain, the combination of two links, each presenting a non-circular opening, a bushing presenting a non-circular part non-rotatably received in the opening of one of said links, said bushing projecting beyond opposite faces of such link, washers encircling such projecting parts of said 10 bushing on opposite sides, respectively, of such link, a pivot received and turning in said bushing and presenting a non-circular part non-rotatably received in the non-circular opening of the other link, and a 15 washer presenting a non-circular opening which non-rotatably receives the non-circular part of said pivot.

9. In a chain, the combination of a cylindrical pivot presenting a slabbed-off flat 25 face, a bushing having a cylindrical opening in which the cylindrical portion of said pivot turns, said bushing having a cylindrical external portion having a slabbed-off flat face, two links pivotally connected by 30 said pivot, one presenting an opening fitting the flat face of said bushing and the other presenting an opening fitting the flat face of said pivot.

10. In a conveyer, the combination of a 35 series of buckets; a series of pivots arranged

in axially aligned pairs, loosely received in bearings presented by said buckets, one pair for each bucket and affording a pivotal support therefor; a series of links arranged in sets, each set affording a support for one pair 40 of said pivots and thus affording a support for the bucket carried by such pivots, each set comprising a pair of links provided substantially midway between their ends with aligned openings which receive one of 45 said pivots; a series of pairs of sleeves, one encircling each pivot and maintaining a minimum spacing of the pair of links by which such pivot is supported; means removably to secure each pivot to its encircling sleeve; a series of shafts connecting both pairs of links of each set and pivotally connecting adjacent ends of said sets of links, each shaft having a flattened terminal portion non-rotatably received in a correspondingly shaped opening in one of said 50 links; a set of bushings encircling each of said shafts, each set comprising two pairs, each bushing having a flattened portion non-rotatably received in one of said links; 60 washers encircling the ends of each bushing; and a series of wheels arranged in pairs, one pair mounted on each of said shafts, each wheel being received between adjacent ends of two pairs of links pivotally connected by the shaft of such wheel.

In testimony whereof, I have signed my name to this specification.

DANIEL W. COE.
